United States Patent Office.

WILLIAM WYATT, OF NASHVILLE, TENNESSEE.

Letters Patent No. 105,289, dated July 12, 1870.

WATER-REGULATOR AND ALARM

The Schedule referred to in these Letters Patent and making part of the same.

To all whom it may concern:

Be it known that I, WILLIAM WYATT, of Nashville, in the county of Davidson and State of Tennessee, have invented a new and improved Water-Regulator and Alarm for Steam-Boilers; and I do hereby declare that the following is a full, clear, and exact description thereof, which will enable others skilled in the art to make and use the same, reference being had to the accompanying drawing forming part of this specification, in which—

Figure 1 represents a side view, partly in section, of my improved water-regulator.

Figure 2 is an inverted horizontal section of the same, taken on the line $x x$, fig. 1.

Similar letters of reference indicate corresponding parts.

The object of this invention is to construct an attachment to steam-boilers, whereby the operation of the feed-pumps will be so regulated as to keep the water in the boiler at the required height; also, to connect with a regulator of this nature an alarm, which will only be worked when the water is below the safety-level.

The invention consists, chiefly, in the combination of a float with a bell-crank and sliding spring valve, by means of which the supply of steam to the pump is regulated.

The invention consists, also, in the further combination therewith of another sliding spring valve and adjustable knob for working the same, for the purpose of working the alarm.

A, in the drawing, represents the steam-pipe which leads from the boiler to the feeding apparatus.

The end of this pipe in the boiler B is closed by a sliding valve, C, which is held closed by a spring, D. a, in fig. 2, represents the seat of the valve D.

To an ear, b, that projects from the pipe A, is pivoted a bell-crank, E, which sustains at the end of its long horizontal arm, c, a pending float, F, of suitable kind.

This float is upheld by the water in the boiler. If the water falls below the requisite level, the float will sink, and will thereby swing the bell-crank, so that the short arm d of the same will strike the valve C and push the same open. The supply of steam to the feed-pump is thereby augmented, to provide for a larger supply of water to the boiler.

The level of the water in the boiler is regulated by means of the float, which is secured to a screw-shank, g, that can be set higher or lower in the arm c.

G is the pipe which leads from the boiler to the alarm-whistle.

It is provided with and closed by a valve, H, which is held against its seat e by a spring, f.

The valve H is opened to blow the alarm by means of the arm d, which is provided with an adjustable knob or screw, h, to blow the alarm only when the water in the boiler is below the safety-level.

Having thus described my invention,

I claim as new and desire to secure by Letters Patent—

1. The float F and bell-crank E, arranged in combination with the sliding spring valve C, and steam-pipe A, as set forth.

2. The alarm-valve H and adjustable knob or screw h, in combination with the water-regulator, as specified.

WILLIAM WYATT.
